SPORT SHIRT

Martin E. Cantor, Bangor, Maine

Application April 30, 1952, Serial No. 19,539

Term of patent 14 years

(Cl. D3—25)

To all whom it may concern:

Be it known that I, Martin E. Cantor, a citizen of the United States, residing at Bangor, in the county of Penobscot and State of Maine, have invented a new, original, and ornamental Design for a Sport Shirt, of which the following is a specification, reference being had to the accompanying drawing, forming part thereof.

The back of the sport shirt is conventionally plain.

I claim:

The ornamental design for a sport shirt, as shown and described.

MARTIN E. CANTOR.
